[57] CLAIM

The ornamental design for a multisided shower curtain ring, as shown and described.

DESCRIPTION

FIG. 1 is a front view of a first embodiment of the multisided shower curtain ring showing our new design;

FIG. 2 is a side view thereof with the opposite side being identical in appearance;

FIG. 3 is a top view thereof;

FIG. 4 is a bottom view thereof;

FIG. 5 is a cross-section view thereof, taken along lines 5—5 of FIG. 1;

FIG. 6 is a front view of a second embodiment of the multisided shower curtain ring showing our new design;

FIG. 7 is a side view thereof with the opposite side being identical in appearance;

FIG. 8 is a top view thereof;

FIG. 9 is a bottom view thereof;

FIG. 10 is a cross-section view thereof, taken along lines 10—10 of FIG. 6;

FIG. 11 is a front view of a third embodiment of the multisided shower curtain ring showing our new design;

FIG. 12 is a side view thereof with the opposite side being identical in appearance;

FIG. 13 is a top view thereof;

FIG. 14 is a bottom view thereof;

FIG. 15 is cross-section view thereof, taken along lines 15—15 of FIG. 11;

FIG. 16 is a front view of a fourth embodiment of the multisided shower curtain ring showing our new design;

FIG. 17 is a side view thereof with the opposite side being identical in appearance;

FIG. 18 is a top view thereof;

FIG. 19 is a bottom view thereof;

FIG. 20 is a cross-section view thereof, taken along lines 20—20 of FIG. 16;

FIG. 21 is a front view of a fifth embodiment of the multisided shower curtain ring showing our new design;
FIG. 22 is a side view thereof with the opposite side being identical in appearance;
FIG. 23 is a top view thereof;
FIG. 24 is a bottom view thereof;
FIG. 25 is a cross-section view thereof, taken along lines 25—25 of FIG. 21;
FIG. 26 is a front view of a sixth embodiment of the multisided shower curtain ring showing our new design;
FIG. 27 is a side view thereof with the opposite side being identical in appearance;
FIG. 28 is a top view thereof;
FIG. 29 is a bottom view thereof;
FIG. 30 is a cross-section view thereof, taken along lines 30—30 of FIG. 26;
FIG. 31 is a front view of a seventh embodiment of the multisided shower curtain ring showing our new design;

FIG. 32 is a side view thereof with the opposite side being identical in appearance;
FIG. 33 is a top view thereof;
FIG. 34 is a bottom view thereof;
FIG. 35 is a cross-section view thereof, taken along lines 35—35 of FIG. 31;
FIG. 36 is a front view of a eighth embodiment of the multisided shower curtain ring showing our new design;
FIG. 37 is a side view thereof;
FIG. 38 is a top view thereof;
FIG. 39 is a bottom view thereof; and,
FIG. 40 is a cross-section view thereof, taken along lines 40—40 of FIG. 36.
